ADAPTOR INSERT FOR A RIBBON SPOOL

John W. H. Bishop, Montreal, Quebec, Canada, assignor
to Bishop Spools, Inc., New York, N.Y., a corporation
of New York

Filed Oct. 2, 1962, Ser. No. 71,961

Term of patent 14 years

(Cl. D41—1)

FIG.1

FIG.2

FIG.3

FIG.4

FIGURE 1 is an isometric view of an adaptor insert for a ribbon spool showing my new design as seen from above;

FIGURE 2 is an isometric sectional view thereof taken substantially along the line 2—2 in FIGURE 1;

FIGURE 3 is a plan view thereof as seen from below; and

FIGURE 4 is an elevational view thereof showing the side opposite that shown in FIGURE 1.

I claim:

The ornamental design for an adaptor insert for a ribbon spool, as shown.
